[57] CLAIM

The ornamental design for a wheel cover for trucks, as shown and described.

DESCRIPTION

FIG. 1 is a perspective view of a wheel cover for trucks showing my new design mounted on a wheel base which is fragmentarily depicted in broken lines for illustrative purposes only;

FIG. 2 is a top plan view thereof;

FIG. 3 is a side elevational view thereof looking in the direction of line 3—3 in FIG. 2;

FIG. 4 is a side elevational view thereof looking in the direction of line 4—4 in FIG. 2; and

FIG. 5 is a bottom plan view thereof.
